Specification of Letters Patent.

Patented Nov. 7, 1916.

Application filed June 30, 1916. Serial No. 106,766.

To all whom it may concern:

Be it known that I, CHARLES J. COOPER, a citizen of the United States, residing at Moline, in the county of Rock Island and 5 State of Illinois, have invented certain new and useful Improvements in Traces, of which the following is a specification.

My invention relates to traces for harness, and particularly refers to improvements in traces constructed with a core of 10 metallic cable which furnishes the necessary tensile strength.

The principal objects of the invention are, to provide a trace of the character described 15 which may be lubricated with no necessity of dismantling or taking apart the various elements of the trace; to provide a trace of the class described in which the applied lubricant is effectually retained by the cable 20 over long periods of time; to provide for a trace of the class described an improved covering which shall be simple and convenient to apply and effect a substantial reduction in the cost of manufacture; to provide 25 improved means for securing said covering in position at the ends of the trace; to provide a covering any part of which may be conveniently and economically renewed when a section thereof shows sign of wear or 30 is destroyed, without the necessity of replacing the entire covering; and, in general to provide an improved trace of the character referred to.

In the drawings which illustrate a preferred embodiment of my invention—Figure 35 1 is a view of the complete trace; Fig. 2 is an enlarged view of one end of the trace, partly in section; Fig. 3 is a similar view to Fig. 2, but entirely in section; Fig. 4 is 40 a sectional view taken on lines 4—4 of Fig. 2; Fig. 5 is a sectional view taken on lines 5—5 of Fig. 2, and Fig. 6 is a full side view of a section of the trace, showing the openings in the leather covering.

45 Referring to the drawings, the trace as a whole is designated as 11 and is provided at each end with clevises 12 and 13 of usual construction, said clevises being substantially alike as to the application of the trace 50 proper and the leather covering therefor. As shown, the trace cable has a central core 14 of hemp or cord around which are helically wrapped a series of stranded cables 15 which taken together make up the wire rope 55 or cable 16 of the trace. The ends of this

wire or cable 16 are secured in the clevises 12 and 13 by threading the latter over the ends of the cable, the ends of which are afterward fanned out so as to substantially fill the socket of the clevis, after which 60 molten metal, preferably spelter, as at 18, is poured into the ends of the clevises and adheres to the fanned out ends 17 of the cable and the sides 20 of the clevises.

Describing the means for covering the 65 cable thus secured to the clevises 12 and 13, 19 represents a leather pocket which covers the socket of the clevis and is made by bending a piece of leather endwise around the socket, the edges being sewed together along 70 each side, as shown. The covering 23 of the cable 16 is an important feature of my invention and comprises a continuous strip of leather wrapped helically around the cable 16 from end to end of the trace. As indicated in Fig. 5 in dotted lines at α , each end of the spiral leather covering 23 is cut obliquely so that when the end of the leather 75 is wrapped around the cable adjacent the socket, the cut end of the leather will encircle the cable. Said oblique end of the leather covering 23 is sewed to the ends 22 of the leather pocket 19, as shown. The joints between the clevis coverings 19 and the helical wrap 23 are protected by metal 80 bands or rings, as shown at 24, which are clasped firmly around the leather and also hold the leather wrapping securely in position without allowing it to become loose or unwrapped. It will be noted that the clevis 90 coverings 19 and the helical wrap 23 are connected or sewed together by a butt joint, as shown in Figs. 2 and 5, thereby rendering the application of the metal band 24 very 85 easy and efficient.

95 By extending the leather clevis coverings 19 beyond the end of the socket and there applying metal bands 24, I support the cable beyond the ends of the clevis socket and thus largely prevent the wires of the cable from 100 bending abruptly at the point where they enter the socket. This construction increases considerably the life of a trace of this character, the tendency of which is to crystallize and break off at the clevis in the course of 105 time, owing to the localized bending of the wires of the cable.

The clevis bolts 21 are of ordinary construction suitable for securing the trace to the collar at one end and the swingletree at 110

the other end. At 26 I have shown a metal loop which may be clamped or clasped on the outside of the trace in order to permit the application of the belly-band of the harness. Said loops 26, or other parts, may be applied at any point in the length of the trace where it is desired to connect other parts of the harness. Such parts may be applied in the same manner as the metal 10 rings 24, to which I have heretofore referred, or in any other suitable manner, as by screw clamps.

An important feature of my invention is the ease with which the trace may be lubricated after the covering has been applied and the trace placed in service. It will be readily understood that a cable used in this manner as a part of the harness and which is exposed to all kinds of weather must be thoroughly 15 oiled or otherwise lubricated in order to prevent rusting of the metal with resultant destruction of the cable. By referring to Fig. 6 it will be observed that when the trace is bent in the arc of a circle, gaps as at 25 are 20 formed in the covering, through which oil, grease, or other lubricant may be applied to the cable core. A convenient way to apply the lubricant is to coil the trace and immerse it in a bath of oil, heated grease, or some other 25 convenient liquid lubricant, when the lubricant will flow into the cable through the gaps 25 in its helical leather covering and fill the hemp core and the interstices between the strands of the cable. If desired, a string 30 of hemp or other porous material may be associated with each strand of the cable so as to provide a considerable storage capacity for the lubricant. Also, a reverse wrap of cotton tape or other similar material may, 35 if desired, be applied to the cable underneath the leather covering.

A trace constructed as I have described will be found to be considerably cheaper to manufacture than any trace which has heretofore been brought to my attention; in 40 addition to which the trace will be found to

be strong, reliable, very durable, and convenient to clean and care for. If a section of the leather covering is destroyed or gives way due to localized wear, it is a simple 50 matter to cut out the defective portion and insert a new strip of leather, abutting ends of the new and old sections of the covering being covered by a metal band, such as shown at 24.

The structural details herein described are merely illustrative of my invention, the scope of which must be determined by reference to the appended claims.

I claim—

1. In a trace, the combination of a wire cable, a clevis in which said wire cable is secured, a covering for said clevis, and a covering for said cable secured to the clevis covering.

2. In a trace, the combination of a wire cable, a clevis in which said cable is secured, a leather covering for said clevis, a helical leather covering for said cable having its end sewed to the clevis covering with a butt 70 joint, and a metal band covering the joint.

3. In a trace, the combination of a clevis provided with a tapered socket, a cable having its end entering said socket and fanned out within said socket, a metal filling for 75 said socket, a leather covering for the socket having a pair of ends extending beyond the end of the socket, and a helical leather covering for said cable and secured to the ends of said clevis covering.

4. In a trace, the combination of a clevis provided with a tapered socket, a cable having its end entering said socket and fanned out within said socket, a metal filling for 80 said socket, a leather covering for the socket having a pair of ends extending beyond the end of the socket, a helical leather covering for said cable and sewed to the ends of said clevis covering, and a metal band surrounding the sewed joint and spaced apart from 85 the end of the socket.

CHARLES J. COOPER.
